United States Patent Office

Des. 232,216

Patented July 30, 1974

232,216

FILING CABINET

Alan Dale Milner, 1150 S. Virain,
Denver, Colo. 80219

Filed Apr. 13, 1970, Ser. No. 22,418

Term of patent 14 years

Int. Cl. D6—04

U.S. Cl. D6—190

Atte 08 JUL

The Figure is a perspective view of a filing cabinet showing my design. The appearance of undisclosed side portions is the same as the sides shown.

I claim:

The ornamental design for a filing cabinet, as shown, and described.
